(57) **CLAIM**

(22) Filed: **Feb. 9, 2001**

The ornamental design for a pad assembly for exercise apparatus, as shown and described.

(51) LOC (7) Cl. **21-02**

DESCRIPTION

(52) U.S. Cl. **D21/694**

FIG. 1 is a front isometric view of a pad assembly for exercise apparatus showing our new design in isolation.

(58) Field of Search D21/662, 673, D21/675, 676, 694, 695; 482/93, 94, 97, 133, 135, 138, 148; D6/601

FIG. 2 is a front elevational view thereof.

(56) **References Cited**

FIG. 3 is a rear elevational view thereof.

U.S. PATENT DOCUMENTS

FIG. 4 is a right side elevational view thereof.
